UNITED STATES PATENT OFFICE.

CHARLES E. SHRINER, FRANK A. SHRINER, AND FRED W. MILLER, OF MONROE,
WISCONSIN, ASSIGNORS TO THE MONROE BURIAL DEVICE COMPANY, OF MONROE,
WISCONSIN.

APPARATUS FOR RAISING AND LOWERING CASKETS.

1,095,168.

Specification of Letters Patent. Patented Apr. 28, 1914.

Application filed April 26, 1911. Serial No. 623,520.

To all whom it may concern:

Be it known that we, CHARLES E. SHRINER, FRANK A. SHRINER, and FRED W. MILLER, citizens of the United States, residing at 5 Monroe, in the county of Green, State of Wisconsin, have invented a new and useful Apparatus for Raising and Lowering Caskets, of which the following is a specification.

10 This invention relates to a new and useful form of apparatus for lowering caskets into graves and, if desirable for raising them from the graves and it also relates to governors for use in connection with the lowering 15 apparatus.

The principal objects of the invention are to improve and simplify the construction of such devices as well as to increase their efficiency in use, and to decrease the expense 20 attending their manufacture, maintenance and operation.

With the foregoing and other objects in view which will appear as the description proceeds, the invention resides in the combination and arrangement of parts and in the details of construction hereinafter described and claimed, it being understood that changes in the precise embodiment of invention herein disclosed can be made within 30 the scope of what is claimed without departing from the spirit of the invention.

In the accompanying drawing forming part of this specification,—Figure 1 is a plan view partly in section of a burial apparatus constructed in accordance with the present invention, the frame of the apparatus being shown in its extended condition; Fig. 2 is a view showing how the apparatus of Fig. 1 is contracted in size, or telescoped, 40 when not in use; Fig. 3 is a detail view in transverse section showing one of the means for permitting free play of the side frame pieces or telescopic members; Fig. 4 is a detail view showing the relative position of 45 the bayonet slots and openings of Fig. 3, as they would appear if the tubular member in Fig. 3 were slotted longitudinally and flattened out; Fig. 5 is a horizontal sectional view through the lower right-hand corner 50 box of Fig. 1, showing the details of the governor mechanism. Fig. 6 is a vertical section through the construction illustrated in Fig. 5; Fig. 7 is a vertical section taken at a right angle to Fig. 6; Fig. 8 is a detail view partly in section showing the centrifugally operated emergency stop illustrated in Fig. 6; and Fig. 9 is a plan of said emergency stop.

55 Like reference numerals indicate corresponding parts in the different figures of the drawing.

The burial apparatus as shown in Fig. 1, is composed preferably of a rectangular frame, which includes the side frame pieces, indicated generally A and B, end frame pieces, 60 indicated generally C and D, and corner boxes indicated generally E, F, G and H.

65 Each of the side frame members A and B includes preferably an intermediate tubular section 1 and end tubular sections 2—3, each 70 of the end sections being approximately half the length of the intermediate tubular section 1 and being slightly larger in diameter than the intermediate section, so as to receive the same in a telescopic manner. The 75 usual belts or straps 20 for raising and lowering a casket are connected to and adapted to be wound on the sections 2 and 3, and the weight of the casket and its contents is sufficient to rotate the sections 2 and 3 and 80 cause the apparatus to operate to lower the casket. The end tubular section 2 of the side member A is rotated, to raise or lower a casket in extreme cases, preferably by means 85 of a handle 4 mounted upon a crank member 5 which is removably mounted at 6 upon a shaft 7 journaled in any suitable manner in the corner box E. The shaft 7 extends entirely through the box E and at its inner end has pinned or fixed thereon a disk 8. 90 The details of the connection between the disk 8 and the tubular section 2 of the side frame A are best shown in Figs. 3 and 4 of the drawing. The disk 8 as shown in Fig. 3, has fixed therein a plurality of radially extending pins 9, preferably three in number. It also is formed with a socket 10 in which is mounted a coiled spring 11 which serves 95 normally to project in a radial direction a movable pin 12. The outer end of the tubular section 2 is formed preferably with three bayonet slots 13—13—13, and an aperture 14, the bayonet slots 13 being adapted respectively to receive the pins 9 of the disk 8 and the aperture 14 being adapted to receive the spring-pressed bolt 12. In assembling the disk 8 and the tubular section 2, the spring pressed bolt or pin 12 is pushed 100

105

inwardly and the pins 9 are caused to register with the outer legs or openings of the bayonet slots 13. The disk 8 is then shoved into the end of the tubular section 2, and rotated slightly, so as to move the pins 9 into the inner legs or extensions of the bayonet slots 13, at which time the bolt 12 snaps outwardly into the slot 14, thus locking the disk 8 within the tubular section 2.

10 It is desirable that the connection between the shaft 7 and the side frame A shall be in the nature of a loose or wobble joint, so that when the apparatus is placed on uneven ground, the corner boxes and side and end frames may conform to the irregularities 15 without interfering with the rotation of the side frame pieces A and B by the descent of the casket. This result is secured preferably by elongating the slot or aperture 14 20 in the tubular section 2 as shown best in Fig. 4, and by widening the inner extensions or legs of the bayonet slots 13 whereby the disk 8 and the pins 9 and 12 thereof may play relatively to the tubular section 1 and 25 at the same time permit constant rotation thereof, this rotation being imparted as before explained, by the descent of the casket.

A worm wheel 15 is mounted on the shaft 7 and connected with the governor mechanism, as hereinafter described.

The means for connecting the tubular section 2 to the intermediate section 1 whereby the parts will rotate in unison, includes a disk 16 which is fixed in any suitable manner on the inside of tube 2 and has fixedly mounted therein a square or non-circular rod 17, the inner upper end of which extends through a square or non-circular opening formed in a disk 18 which is fixed in any 40 suitable manner in the one end of the intermediate section 1. At its inner end the rod 17 is provided with an enlargement or head 19 which serves to limit the relative movement of the tubes 1 and 2. Tube 1 is of course rotated with the tube 2 because of the disk 16, non-circular rod 17, and disk 18. The arrangement of the disk 16, rod 17, disk 18 and nut 19 is duplicated in the end tubular section 3 of the side frame A, for the 45 purpose of connecting the parts at the telescoping point and causing the sections 2 and 3 to rotate in unison.

The side frame B is a duplicate of the side frame A, being composed of the three 55 telescopic sections arranged so that sections 2 and 3 of said frame are caused to rotate in unison.

The usual belts or straps 20 for raising or lowering the casket are adapted to be wound 60 upon the inner end of sections 2 and 3 of the side frame pieces A and B, as shown in Fig. 1.

The means for causing frame pieces A and B to rotate in unison so as to cause both 65 the ends of the straps 20 to be simultane-

ously wound or unwound will now be described.

A disk 21 is loosely and detachably engaged with the tubular section 3, in the same manner as the disk 8 is connected with the tubular section 2 in Fig. 3, so as to produce a loose joint which can be detached or disassembled when necessary or desirable. The disk 21 is secured to a shaft 22 journaled in the corner box F, and has fixed thereto a bevel wheel 23, which is in mesh with a bevel wheel 24 fixed on a square or non-circular rotatable shaft 25 provided at its end with a nut or head 26. The non-circular shaft 25 extends through a non-circular opening formed in a tubular member 27 of the end frame piece D. This tubular member 27 has fixed on the end thereof in the corner box G a bevel wheel 28 which is in mesh with bevel wheel 29 fixed on a shaft 30 which, by means of the form of loose joint illustrated in Fig. 3, is caused to rotate with the side frame piece B. It will be obvious that the tubular member 27 can slide or telescope upon the non-circular shaft 25. For the purpose of bracing and supporting the tubular member 27 and non-circular shaft 25, the corner box G is provided with a tubular member or extension 31 and the corner box F is provided with 35 a similar extension 32, the extension 32 being fitted into the extension 31, so as to telescope therein.

The side frame piece B at its lower end in Fig. 1 is journaled in the corner box H, 100 by means such as the stud shaft 33 having an enlargement or head 34, said stud shaft 33 being provided with a disk such as 8 in Fig. 3 having a detachable connection with the tubular section 2 of the side frame 105 piece B.

The corner boxes E and H are telescopically connected with each other by means such as the tubular extensions 35-36. Each of the outer tubular sections 35 and 31 has 110 an extended spring-pressed pin 37 adapted to engage slightly elongated slots 38 in the extensions 36 and 32, respectively, whereby to permit slight play of the sections 35 and 36 when extended. When it is desired to 115 collapse the end frame piece C the spring-pressed pin 37 is pressed outward until it ceases to engage the slot 38 after which the sections 35 and 36 can be telescoped. When they are again extended the pin 37 automatically snaps inward into the slot 38 registering therewith. The spring-pressed pins can be arranged on the inner tubes 36 and 32 if preferred and snap outwardly into the outer tubes.

From the foregoing description of the burial apparatus, it will be apparent that the rectangular frame when not in use can be telescoped into small compass, as indicated in Fig. 2, and that if desired the side 120 125 130

frame pieces A and B can be entirely detached from the corner boxes for convenience in shipping the apparatus. More sections can be used, if desired, in the side and end frame pieces to permit greater telescopic action.

Governor mechanism.—The governor mechanism will next be described with particular reference to Figs. 5 to 9 inclusive. 10 This governor mechanism preferably includes a worm wheel 15 which is mounted loosely on the main operating shaft 7. It is desirable that the governor mechanism shall be so arranged that the shaft 7 and side 15 frame pieces A and B will freely rotate to lower a casket and that the governor mechanism should come into play while the casket is being lowered. A ratchet wheel 40 which is fixed in any suitable manner on the shaft 20 7, as shown in Figs. 5 and 7, and is engaged by spring-pressed pawls 41 which are pivotally mounted upon the worm wheel 15 to thereby permit free rotation of the shaft 7 in one direction and to permit the rotation 25 of the shaft in the opposite direction to be transmitted through the pawls 41 to the worm gear 15. The worm gear 15 is in mesh with a worm 42 formed on a shaft 43 which is suitably journaled in the corner 30 box. The shaft 43 at its lower end has fixed thereto a worm wheel 44 shown best in Figs. 6 and 9 of the drawing.

In the event that for any reason the casket should descend too rapidly, it is desirable 35 that emergency means be provided for overcoming this descent. The means for accomplishing this result preferably includes a lever 45 which as shown in Fig. 9 is fulcrumed at 46 upon the worm wheel 44 and 40 at its free end 47 held normally against a stop pin 48, and thus within the periphery of the worm wheel 44, by means such as the coil spring 49. In the event that the apparatus should speed up, the weighted outer end 45 47 of the lever 45 will through centrifugal action swing outward beyond the periphery of the gear wheel 44, and will thus engage the stop or projection 50 mounted adjacent the periphery of the worm wheel 44, to 50 thereby check the operation of the governor mechanism and the descent of the casket. A stop 51 is provided to limit the outward swinging movement of the emergency lever 45 after it has moved outward far enough to 55 engage the projection 50 shown in Figs. 6 and 8. This governor mechanism will operate to retard the operation of the lowering mechanism while a corpse of ordinary weight is being lowered. If however the 60 weight of the casket and its contents should be excessive and thus accelerate the speed of the lowering mechanism to an undesirable extent, the lever 45 of the emergency stop would swing outwardly and thus move into 65 engagement with the projection 50. This

will check the operation of the mechanism in the manner hereinbefore set forth and, should it be desired to release the lever 45 from engagement with the projection 50, it is merely necessary to slightly wind the 70 strap 20 so that said lever 45 will not bind against projection 50 whereupon spring 49 will retract the lever against the stop pin 48. By then releasing the mechanism the lowering operation will continue as before. 75 It is to be understood, of course, that other means than those described may be provided for disengaging the lever 45 from the stop 50 should the two parts become bound together so as to stop the lowering operation. 80

The worm wheel 44 is in mesh with a worm 53, Fig. 7, which is formed upon a regulator shaft 54 suitably journaled in the corner box. The shaft 54 has thereon a fixed collar 55 and a longitudinally movable 85 collar 56, the collars 55 and 56 being connected with each other by bow springs 57 which are provided with centrifugally operated governor weights or balls 58, whereby as the rotation of the shaft 54 causes the 90 governor balls 58 to swing outward, the movable collar 56 is drawn downward toward the fixed collar 55. The movable collar 56 has fixed thereon a disk 59. The disk 59 is adapted to move downward, with the collar 56, into contact with a disk 60, which, as shown in Figs. 5 and 7, is mounted eccentrically upon a shaft 61 journaled in the corner box and having at its outer end a crank 62 formed with a lock pin or handle 100 63 surrounded by a spring 64 which serves to force it normally into engagement with any one of a circularly arranged series of sockets 65 formed in the corner box, whereby by pulling the handle 63 outward against the action of the spring 64 the shaft 61 can be rotated so as to produce any desired amount of friction between the eccentric disk 60 and the rotary disk 59, after which by releasing the handle 63, the spring 64 105 will cause the same to be locked in adjusted position. 110

The operation of the governor mechanism is thought to be obvious from the foregoing description in connection with the drawing. 115

What is claimed as new is:—

1. Burial apparatus including a frame having corner boxes, shafts journaled therein, disks secured to the shafts, tubular members connected to and revoluble with the 120 disks, flexible supporting members secured thereto and adapted to unwind therefrom under the weight of a supported casket, shafts housed and centered in and revoluble with said members, a tubular section telescopically connected to said members and having its ends slidably engaging and rotating with said housed shafts, end connections between the boxes, governing means carried by one of the boxes, and 125 130

means in one of the end connections and in the adjacent boxes for operatively connecting the members at one side of the frame to the members at the other side of the frame 5 to insure rotation of the members in unison.

2. Burial apparatus including a frame having corner boxes, shafts journaled therein, disks secured to the shafts, tubular winding members connected to and revoluble 10 with the disks, angular shafts housed and centered in and revoluble with said members, a tubular section telescoping into said members and having its ends slidably engaging and rotating with the angular shafts, 15 flexible devices connected to and adapted to be wound on said members, telescopic end connections between the boxes, means in one of the end connections and in the adjacent boxes for transmitting motion from the 20 members at one side of the frame to the members at the other side of the frame, and actuating means carried by one of the other boxes.

3. In burial apparatus the combination 25 with means for raising and lowering a casket, of a governor therefor comprising in combination a main shaft, a ratchet fixed thereon, a worm wheel loose thereon, an automatically operated pawl on said worm 30 wheel engaging said ratchet, a worm shaft engaging said worm wheel, a second worm wheel fixed on said worm shaft, a pivotally mounted arm on said second worm wheel, constituting an emergency stop, means for 35 holding said arm in inoperative position, means for engaging said arm when in operative position to stop the rotation of said second worm wheel, a second worm shaft meshing with said second worm wheel, a 40 fixed and a movable collar on said second worm shaft, bow springs connecting said collars and provided with governor and weights, a disk connected with said movable collar, an eccentric disk having its axis radial to the 45 axis of said second worm shaft, a crank member connected with said eccentric disk, and a spring operated handle member connected with said crank and serving to lock said eccentric disk in different positions of 50 adjustment.

4. In a device of the character described, the combination with supporting straps, a pair of rotatable sleeves to which said straps are secured, a plurality of heads in which 55 said sleeves terminate and on which said sleeves are rotatably mounted, means whereby said sleeves rotate synchronously, a governor to control the rotation of said sleeves when a weight is placed upon said straps, 60 and a pawl and ratchet and worm and worm

wheel interposed between said sleeves and said governor.

5. In a device of the character described, the combination with straps adapted to support a casket, a pair of rotatable elements to 65 which said straps are secured, means for supporting said elements, means whereby said elements rotate synchronously, and a centrifugal governor to control the rotation of said elements when a weight is placed 70 upon said straps.

6. In a device of the character described, the combination with supporting straps, a pair of rotatable sleeves to which said straps are secured, means for supporting said 75 sleeves, means whereby said sleeves rotate synchronously, a centrifugal governor to control the rotation of said sleeves when a weight is placed upon said straps, and a worm and worm wheel interposed between 80 said sleeves and said governor.

7. In a device of the character described the combination with straps adapted to support a casket, rotatable means to which said straps are secured, means for supporting 85 said rotatable means, means whereby said rotatable means are rotated synchronously, and a centrifugal governor adapted to control the rotation of said rotatable means when the same is rotated due to a weight 90 placed upon said straps, said governor having an emergency stop operative upon undue increase in speed of said governor.

8. In a device of the character described, the combination with supporting straps, a 95 pair of rotatable sleeves to which said straps are secured, a plurality of heads in which said sleeves terminate and on which said sleeves are rotatably mounted, means whereby said sleeves rotate synchronously, a governor to control the rotation of said sleeves when a weight is placed upon said straps, a worm and worm wheel, a bearing in said head through which the worm wheel shaft projects, the protruding extremity of said 100 shaft being adapted to receive a handle to wind up said straps upon said sleeves, said governor including a friction disk, and a cam co-operating with said friction disk to 105 control the speed of said governor. 110

In testimony that we claim the foregoing as our own, we have hereto affixed our signatures in the presence of two witnesses.
